UNITED STATES PATENT OFFICE.

JOHN F. MURPHY, OF MINNEAPOLIS, MINNESOTA, ASSIGNOR TO FLOUR CITY ORNAMENTAL IRON WORKS, OF MINNEAPOLIS, MINNESOTA, A CORPORATION.

DOOR-HANGER.

1,038,938.

Specification of Letters Patent. Patented Sept. 17, 1912.

Application filed June 19, 1911. Serial No. 634,044.

To all whom it may concern:

Be it known that I, JOHN F. MURPHY, of Minneapolis, Hennepin county, Minnesota, have invented certain new and useful Improvements in Door-Hangers, of which the following is a specification.

My invention relates to operating mechanism for double, or what is generally known as "center parting" doors, or the type where the movement of one door in one direction will cause a corresponding movement of the other door in the opposite direction.

Doors of this kind are in general use and the primary object of my invention is to improve the hanger and operating mechanism therefor.

The door is adapted for a variety of uses but is designed particularly for use in elevator shaft openings for closing the entrances to the shaft at different elevations.

The invention consists generally in various constructions and combinations, all as hereinafter described and particularly pointed out in the claims.

In the accompanying drawings forming part of this specification, Figure 1 is a front view of the upper portions of the center parting doors, showing my improved operating mechanism, the doors being in a closed position, Fig. 2 is a similar view, showing the doors in a partially open position, Fig. 3 is a sectional view, showing in detail the operating mechanism, Fig. 4 is a transverse sectional view showing the construction of the track, Fig. 5 is a view showing the doors in their closed position and the means for locking them.

In the drawing, 2 represents a suitable bracket whereon the track is supported. The lower track consists of side plates 3 and an intermediate plate 4 projecting above the side plates and secured thereto. The plate 4 is of less width than the plates 3, thereby forming a centrally arranged groove or recess 5 in the underside of the track. 6 and 7 are the door sections, the former being provided with a bracket 8 on which a rack bar 9 is mounted that is slidable in the recess 5. Above the door section 6 a carriage 10 is provided, having rollers 11 provided with centrally arranged annular grooves 12 which receive the upper edge of the plate 4, the flanges of the rollers on each side of the grooves resting upon the plates 3 and supported thereby, the plate 4 merely serving

as a guide to hold the rollers in place on the plates 3. The door section 7 has a similar carriage 10^a provided with rollers 11^a, which have substantially the same functions and operate in substantially the same way as the 60 rollers 11. Secured to the lower track are brackets 13 having bearings for pinion 14. This pinion is interposed between the upper and lower tracks within a recess 15 in the lower track and its teeth mesh with those of 65 the rack bars, as will hereinafter appear. Guiding rollers 16 and 17 are mounted on the brackets 13. The upper track is made in two sections and consists of side plates 18 and an intermediate plate 19 which is narrower than 70 the side plates to form a recess 20 between them. The door section 6 is connected by hangers 21 and 22 with one of the upper track sections and similar hangers connect the door section 7 with the other track sections. The second track section I will designate by the same reference numeral with the addition of the exponent "a".

In the recess formed in the upper track sections a rack bar 22' is adapted to slide 80 and is secured to the door section 7, its teeth meshing with the pinion 14 and held in engagement therewith by the roller 16, while the roller 17 has a corresponding function for the rack bar 9. When, therefore, 85 one door is pushed open, as, for instance, the door section 6, its movement will revolve the pinion 14 from right to left and through its toothed connection with the rack bar 22' will slide the door section 7 90 in the opposite direction or toward the left, thus moving the door sections away from one another and exposing the opening. During this movement the carriages 10 and 10^a will slide in their bearings, the rollers 11 95 and 11^a being idle and accommodating themselves to the position of the rack bars and operating merely as antifriction supports for the sections of the upper track. Door sections mounted in this way can be 100 easily operated, the rack bars sliding freely back and forth on the carriages and enabling the operator to open or close the doors with but little effort.

I prefer also to provide in connection 105 with this device a locking means, consisting of a sliding latch or bolt 23 mounted in guides 24 on one of the doors and having an upper end adapted to engage a catch 25 on the bracket 13. To release the doors this 110

bolt is pushed up and when disengaged from the latch the doors will be released and may be opened.

It will be obvious that the rollers 11 and 5 11^a may have peripheral ribs formed thereon instead of annular recesses therein, in which case the tracks would have recesses to receive these ribs instead of ribs to enter the annular recesses of the rollers. This, 10 however, is merely a reversal in the construction and I have not thought it necessary to illustrate the modification herein.

I claim as my invention:—

1. The combination, with a stationary 15 track having a longitudinal groove or recess in its underside, of carriages and anti-friction rollers therefor adapted to rest and roll on the upper side of said track, upper movable track sections and hangers secured 20 thereto, independent door sections supported by said hangers respectively, said upper track sections bearing on said anti-friction rollers and movable thereon, said upper track sections having centrally arranged, longitudinal grooves or recesses in 25 their under surfaces, a pinion interposed between said upper track sections and said stationary track, and rack bars attached to said door sections respectively and slidable 30 in the grooves in said stationary track and in said upper track sections, one of said rack bars being above said pinion and meshing with the teeth thereof, and the other of

said rack bars being located beneath said pinion and meshing with the teeth thereof. 35

2. The combination, with a stationary track having a raised central portion and bearing surfaces on each side thereof, and a longitudinal recess in its underside, of carriages having anti-friction rollers provided 40 with annular grooves adapted to receive the raised central portion of said track, the flanges of said rollers on each side of said grooves resting and rolling on the bearing surfaces of said track, door sections and hangers therefor, upper track sections carried by said hangers and having longitudinal recesses in its underside, the walls of said recesses resting on the flanges of said rollers and supported thereby, a pinion interposed in said stationary track, rack bars arranged above and below said pinion and meshing therewith, one of said rack bars being attached to one door section and sliding in the recess in the underside of said stationary track, and the other rack bar being attached to the other door section and sliding in the recess of said upper track sections and in the annular grooves of said rollers; substantially as described. 50 55 60

In witness whereof, I have hereunto set my hand this 14th day of June, 1911.

JOHN F. MURPHY.
